UNITED STATES PATENT OFFICE.

NEIL T. ALBRIGHT, OF KOKOMO, INDIANA, ASSIGNOR TO KOKOMO AUTOMOTIVE MFG. CO., OF KOKOMO, INDIANA, A CORPORATION.

SIGNAL LAMP.

Application filed March 28, 1924. Serial No. 702,531.

To all whom it may concern:

Be it known that I, NEIL T. ALBRIGHT, a citizen of the United States, and a resident of Kokomo, county of Howard and State of Indiana, have invented a certain new and useful Signal Lamp; and I do hereby declare that the following is a full, clear, and exact description thereof, reference being had to the accompanying drawings in which like numerals refer to like parts.

This invention relates to a combination stop and direction signal to be mounted on the rear of a vehicle and electrically illuminated for signal purposes. However, the invention resides only in the peculiar features of the signal as herein claimed. Heretofore signals of this character have been constructed having oppositely directing arrows, or the words "Left" and "Right" or abbreviations thereof in combination with an individual and separate stop or caution signal, all three, i. e., the stop, left and right signals being operated independently of each other and entailing three separate compartments having three separate bulbs for illuminating the individual signals.

It is the object of this invention to provide a signal of this character eliminating one of the three compartments, bulbs and signals by employing direction arrows or similar direction indicating signs which may be illuminated separately or independently of each other as desired, and combining the two by illuminating them both simultaneously for providing and giving a stop or similar signal. This construction will obtain certain advantages over the old structure both as to operation, cost and reduction in space, as will be hereinafter more fully pointed out.

Another feature of the invention resides in the means for controlling the signal, whereby the direction signals may be operated manually when it is desired to make a turn, while the stop or warning signal may be operated automatically by the brake or clutch of the vehicle, both mechanical and automatic operating means being combined so as to necessitate little attention from the operator of the vehicle.

Still another feature of the invention resides in the specific mechanical structure of the signal lamp, whereby it may be readily cast in two pieces and assembled for providing the desired outline, partitions and

lamp sockets, as illustrated in the drawings 55 and hereafter more specifically described.

The full nature of the invention will be understood from the accompanying drawings and the following description and claims:

In the drawings, Figure 1 is a diagrammatic illustration of the control system. Fig. 2 is a front elevation of the assembled lamp. Fig. 3 is a section taken on the line 3-3 of Fig. 2. Fig. 4 is a front elevation 65 of the assembled members without the lens or door mounted thereon. Fig. 5 is a front elevation of the outer member. Fig. 6 is a front elevation of the inner member. Fig. 7 is an end view of the inner member as 70 shown in Fig. 6.

In the drawings there is shown an automobile signal lamp comprising a housing 10 shaped as shown in Fig. 5, the same having an open end which is closed by the closure 75 11 securing the lens 12 thereover. The rear of the housing is provided with a screw threaded projection 13 on which a cap 14 is screwed for securing the conduit tube 15 in place.

The casting comprising the housing, as shown in Fig. 5, is provided with an aperture 16 which is surrounded by the screw threaded projection 13, and is formed on the inner surface with inwardly projecting 85 lugs 17, 18 and 19 provided midway their depth with recesses 20, 21 and 22, into which or against which the insert partition member 23 may be seated and held in place.

The insert member 23 is likewise cast of 90 suitable metal with a back closure 24, the sides thereof providing the shape of the arrows, as shown in Fig. 6, with a partition wall 25 separating the arrows and joining with the partition wall 26, which separates 95 the arrows from the lower portion or tail-light compartment 27. Cast in the tail-light compartment there is a lamp socket 28 and cast in each of the arrow sections there are lamp sockets 29 and 30.

In assembling the insert member 23 into the casing, the points 31 will seat in the recesses 20 and the points 32 will seat in the recesses 21, whereas the ends 33 of the casting will abut the recesses or shoulders 22. It will be further observed that the socket 28 will be in alignment with the aperture 100 16, and that upon securing the lens and door

11 in place, the insert member will be held firmly in position, thereby giving desired outline effect of the oppositely directed arrows and the tail-light compartment, as shown in Figs. 2 and 4.

In the operation of the signal, reference being had to Fig. 1, there is provided a hand operated switch 38 having a left contact and a right contact. The switch member 38 is connected with the ignition switch 39. The left contact is connected through the wire 40 with the bulb 35 and the right contact is connected through the wire 41 with the right bulb 36. The ignition switch 38 is connected through the wire 42 with the automatic switch 37 operated by either the brake or the clutch, said switch being connected through the wires 43 with the respective bulbs 35 and 36. The tail light bulb 34 is connected with the tail light circuit in the usual manner through the wire 44.

When the operator wishes to make any turn, he manually turns the switch 38 to the direction to be taken. This will be illustrated by assuming that he desires to turn to the left. He accordingly turns the switch to the left as he is approaching the turn. This will cause contact to be made from the ignition switch through the wire 40 directly to the bulb 35 and will illuminate the bulb and the compartment defined by the left direction indicating arrow. As he slows down to make the turn, by either throwing out his clutch or putting on his brake, a current will also pass from the ignition switch through the line 42, switch 37 and wires 43 to both lamps 35 and 36, thereby illuminating both of the arrow-like compartments. This will indicate the stop signal or other warning signal by reason of the added illumination throughout the entire width of the lamp. Upon releasing the brake or clutch to make the turn, the stop signal will be shut off, or rather both arrows will cease to be illuminated, but the left turn signal will remain illuminated until it is manually switched off by the operator. If it is desired to slow down or make a stop without making a turn, the operation of the brake or clutch will illuminate both lamps 35 and 36, thereby flashing the entire expanse of signal lamp and giving the warning signal.

The above example is only for purpose of illustration, it being apparent that other arrangements for controlling a lamp of this

character may be employed without departing from this invention.

The invention claimed is:

1. A signal lamp comprising a casing cast integral with a back portion and an open face, said back portion having an aperture formed therein, an insert casting forming a plurality of compartments outlined in the shape of oppositely directed arrows extending in alignment with each other having their blunt ends abutting the walls of said casing and insert casting being provided with interengaging means whereby the latter is supported within the former, and snugly seated within said casing a transparent closure removably secured over the open face of said casing, and individual means in each of said arrows for illuminating the same, whereby said illumination will be apparent through said closure in the outline of the respective combined arrows, substantially as shown and described. 60

2. A signal lamp comprising a casing cast integral with a back portion and an open face, said back portion having an aperture formed therein, a plurality of inwardly extending projections formed in said casing, an insert casting forming a plurality of compartments outlined in the shape of oppositely directed arrows, said casting being adapted to fit snugly within said casing and be seated and held in position by said projections, and a closure removably secured over the open face of said casing for securing said insert casting therein. 75

3. A signal lamp comprising a casing cast integral with a back portion and an open face, said back portion having an aperture formed therein, a plurality of inwardly extending projections formed in said casing, an insert casting forming a plurality of compartments outlined in the shape of oppositely directed arrows, a compartment being positioned below the direction indicating compartments for receiving a tail light, said casting being adapted to fit snugly within said casing and be seated and held in position by said projections and spaced from the rear of the casing, a socket formed integral with said insert casting in each of said compartments for receiving a lamp, and a closure removably secured to said casing for holding said insert member in place therein. 90

In witness whereof, I have hereunto affixed my signature.

NEIL T. ALBRIGHT.
